UNITED STATES PATENT OFFICE.

FREDRIK WILLE, OF WARREN, OHIO, ASSIGNOR TO THE TRUMBULL STEEL COMPANY,
OF WARREN, OHIO, A CORPORATION OF OHIO.

ROLLING MILL.

Application filed February 28, 1922. Serial No. 539,632.

To all whom it may concern:

Be it known that I, FREDRIK WILLE, residing at Warren, in the county of Trumbull and State of Ohio, a citizen of the 5 United States, have invented or discovered certain new and useful Improvements in Rolling Mills, of which improvements the following is a specification.

My invention relates to improvements in 10 rolling mills and particularly mills for rolling small sections of great and indefinite length, such as rods and strips. The invention lies in organization such as makes for economy in mill lay out, economy in operation, and speed of production.

In the accompanying drawing I show in 15 plan and diagrammatically a hot strip jobbing mill in which my invention is found. The invention, it will be understood, is not 20 limited in its applicability to mills of this particular kind or class. The showing is in this respect exemplary.

The word mill is in this art used with 25 different grades of meaning; the whole organized mechanical unit, whereby a billet is rolled to a strip is called a mill; again parts of this unit are specially designated, as roughing mill and finishing mill; yet again, a single stand of rolls is, in the abstract 30 sense, and often in concrete use of language, a mill. I shall use the word mill without qualification in the first and general sense only.

The mill here shown includes a billet heating furnace 1, a roughing mill 2, and finishing mills 3, 4, and 5. The invention lies not 35 in the particular construction of roughing mill or of finishing mill or of their parts; it lies in the organization of a plurality of 40 finishing mills of diverse character with one roughing mill, and in a correlated elaboration in the construction of the heating furnace, whereby the mill as a whole is rendered "elastic", to roll a wide variety of 45 shapes, and at the same time its output as a jobbing mill is greatly increased.

The heating furnace 1 is double. The effect is that of two furnace parts set end to end, with intake at their remote ends and 50 pushout in the middle,—that is to say, at the meeting line of the two furnace parts. From a billet storage platform 11 two charging skids 12 lead oppositely to two charging conveyors 13. In the line of the

conveyors shears 14 may be arranged, beyond 55 which shears the conveyed material reaches pushers 15, one of which stands opposite each of the two ends of the heating furnace 1. The pushout is indicated at 16. This double construction of heating furnace of 60 course doubles the capacity of this part of the mill. Twice as much material may be prepared in a given time for rolling as with a single heating furnace. And this increased capacity is gained with incidental 65 economies. For example, one man can tend the pushout and deliver a double quantity. If there were two separate and independent heating furnaces there would have to be two attendants to do the same work.

The roughing mill 2 is in no respect unusual. As shown, it consists of two sets of roll stands. The second set in the course of progress of material under treatment is sometimes called the intermediate mill, to 75 distinguish it from the first set of roll stands, to which the name roughing mill is then more narrowly confined. Of the roughing mill (used in application collectively to these two sets of roll stands shown) it suffices to say that if the three finishing mills presently to be described were organized, each with its own roughing mill, the roughing mills would be substantially identical. The single mill 2 is then a mill suitable to 80 serve any one of the three finishing mills.

The finishing mills, of which as has been said and as the drawing shows there is a plurality, include mills of two types: a continuous mill 3, and in this case two looping 90 mills, 4 and 5. Speaking abstractly, the continuous mill occupying but little space and operating automatically produces material at great speed; it is, however, best suited to the production of material of relatively 95 heavy section. The looping mill is best suited to the production of lighter material.

The continuous mill here shown is typical; its rolls are conveniently driven from a single motor, as indicated. Associated with 100 it are conveniently arranged a runout table 31, a mechanical cooling bed 32, a shear table 33, a shear 34, and a cradle 35 for receiving the sheared lengths of cold material.

The two finishing mills 4 and 5 are essentially alike, consisting each of a plurality of roll stands. Associated with each finishing mill are runout tables 41, 42, 51, 52,

and straightening beds 43, 53, shears 44, 54, and reels 45, 55. The shears and the reels, it will be understood, are movable, and may be shifted to any point desired across the ends of beds 43, 53, and the reels may be duplicated at opposite ends of the beds, as indicated at 44^a, 54^a.

The number of roll stands making up the two looping mills are, as shown, different, and by such provision the two mills may, if desired, be adapted for the production of material of different degrees of fineness. The mills may be so arranged that either all or part of their roll stands may be involved in a given operation. To this end, runout tables 42, 52 lead from intermediate roll passes, while tables 41, 51, lead from the ultimate passes of the two mills. The ultimate roll stand 46, 56 of each of the two finishing mills is here shown to be driven by its own motor, separate from the motor which drives the rolls of the other stands. This is a feature whose benefits and advantages are dwelt upon at length in the application of Henry G. O'Brien, of United States Letters Patent, filed September 4, 1919, Serial No. 321,660. Suffice it here to say that these features,—diversity between the two looping mills in the number of roll stands, the possibility of using part only of the roll stands of either mill, and the separate drive of the rolls of the ultimate roll stand,—all make for adaptability and flexibility of the mill as a whole to produce material to any specification—such of course being the desideratum of a jobbing mill.

The invention lies in the assembly with one roughing mill, of, first, the plurality and diversity of finishing mills described, and, incidentally to that (and as a matter of substantive invention as well), a billet heating furnace of the arrangement and

organization described. The gains and advantages of the invention are, first, the relatively great service got out of the roughing mill, and the consequent economy; the adaptability of the mill to a wider range of product than any simpler organization can produce; the possibility of making repair and replacement on one finishing mill while operation on others continues, thus avoiding the undesirable idleness of one part, though itself in condition for service, incidentally to repair work done on another and associated part. That is to say, any portion of the three finishing mills shown may be put temporarily out of commission while the other portion remains in commission. This means of course capacity for high production.

I claim as my invention:

1. A rolling mill assembly including a single roughing mill, a heating furnace provided with a plurality of charging intakes and a single push-out and adapted to deliver heated billets to the roughing mill, and a plurality of finishing mills adapted to be served by the roughing mill.

2. A rolling-mill assembly including a single roughing mill in operative combination with a plurality of finishing mills, one of said finishing mills being a looping mill, separate means for driving the rolls of the ultimate pass of the looping mill, means for conveying away the material from such ultimate pass of the looping mill, and means for conveying away the material from a pass of the looping mill anterior to the ultimate.

In testimony whereof I have hereunto set my hand.

FREDRIK WILLE.
